UNITED STATES PATENT OFFICE.

WILLIAM C. PERKINS, OF ROCKY HILL STATION, KENTUCKY.

CAR-COUPING.

SPECIFICATION forming part of Letters Patent No. 602,914, dated April 26, 1898.

Application filed December 21, 1896. Serial No. 616,478. (No model.)

To all whom it may concern:

Be it known that I, WILLIAM C. PERKINS, a citizen of the United States, and a resident of Rocky Hill Station, in the county of Edmon- 5 son and State of Kentucky, have invented cer- tain new and useful Improvements in Car- Couplings, of which the following is a speci- fication.

My invention relates especially to couplings 10 in which a link and spring-pressed latch-lever are employed, and it also relates to couplings wherein a propeller or spring-controlled block is supported in the coupling-head, the said spring-pressed latch-lever and block serving 15 to receive the blow from the link when the latter is projected forcibly therein; and my invention consists in certain details of construction and combinations of parts hereinafter particularly described and claimed.

20 In the accompanying drawings, which illustrate my invention, Figure 1 is a side elevation, partly in section, with the link coupled on one side and uncoupled upon the other, of my improved coupling and showing the adjacent parts of box-cars; Fig. 2, a front elevation thereof and of the adjacent parts of the car; Fig. 3, a side elevation of a draw-head and single coupling and link attached to a car, and Fig. 4 a plan of the parts as shown 25 in Fig. 3.

The draw-head A is attached to the draw- 30 bar B and is held upon the framing of the car C by straps D, which admit of a limited end- wise movement thereon, and a buffer-spring 35 E upon said draw-bar receives the impact of the draw-head in a well-known manner.

The draw-head A has a central longitudi- 40 nal aperture a extending rearwardly from the link-recess a' and receives a propeller F, pro- vided with a rearwardly-projecting guide-pin f, a bearing-plate f' to support the rear end of the guide-pin, and a spiral spring f'', which encircles said pin and presses between the propeller and bearing-plate, thus serving to 45 hold the propeller forward and allow it to receive the blow from the link and provide a cushion therefor.

The link-recess a' in the draw-head crosses 50 horizontally a vertical recess a'' to receive the latch G, and is angular at the bottom below the link-recess to provide a solid abutment

for the free end of the said latch. The latch G is curved or elbow-shaped, and its ends project rearwardly, one end to provide an operating-lever g and the other end to provide a 55 latch-plate g'. A pivot-pin g'' at the elbow of the latch passes horizontally through the draw-head and holds the latch to swing freely in the vertical recess of the draw-bar to cross the horizontal link-receiving recess. 60

The pivoted elbow-shaped latch G is held down firmly when not lifted by springs g'', se- cured at their forward ends to the draw-head upon each side of the said latch-lever and se- cured also to the lever g of the latch. The 65 free end of the latch is notched at g' to bite or take hold of the link H and by the spring- pressure exerted thereon hold the same hori- zontally with a yielding pressure to direct it into the link-recess of the opposing draw- 70 head.

The latch is lifted by means of a chain I, connecting the end of the latch-lever g with the free or swinging end of a lever K, secured to a rock-shaft L, which is supported horizon- 75 tally in bearings l upon the end of the car. Crank-arms l' at the ends of the rock-shaft admit of the latch being operated from the sides of the car, and a rod l'' is connected to the lever K and extends to the top of the car 80 within reach of the brakeman.

The curved edge of the latch rides freely over the link as it is projected beneath it, the notched end thereof is pressed firmly down upon the end of the link by the springs, 85 and the lower forward edge of the latch abuts against the inclined wall of the recess, and thus securely holds the link at all times in proper working position and securely against the strains to which it is subjected. 90

I claim as my invention and desire to se- cure by Letters Patent—

A car-coupling comprising a two-part draw- 95 head having a horizontal link-recess, a longi- tudinal propeller-recess, and a vertical recess, an elbow-shaped latch located in the vertical recess, and a spring-actuated propeller-block located in the longitudinal recess, the said pro- peller-recess extending part through the inner 100 end of the link-recess and communicating at a point coincident with the vertical recess, form- ing a shoulder against which the propeller-

block normally abuts to hold the same slightly in the rear of the path of travel of the latch, the draw-head section being divided horizontally in the line of the propeller and link-recess to admit of the removal and repair of the spring-actuated propeller-block substantially as described.

In testimony that I claim the foregoing as my invention I have signed my name in the presence of two subscribing witnesses.

WILLIAM C. PERKINS.
